A. G. ENS

GRAIN SAVING ATTACHMENT FOR BINDERS

Filed Dec. 31, 1923

FIG. 1.

FIG. 2.

FIG. 3.

INVENTOR
ABRAHAM G. ENS
BY *William S. Fowler*
ATTORNEY

UNITED STATES PATENT OFFICE.

ABRAHAM G. ENS, OF BLUMENHOF, SASKATCHEWAN, CANADA.

GRAIN-SAVING ATTACHMENT FOR BINDERS.

Application filed December 31, 1923. Serial No. 683,710.

To all whom it may concern:

Be it known that I, ABRAHAM G. ENS, a citizen of the Dominion of Canada, and resident of Blumenhof, in the county of Moose Jaw and Province of Saskatchewan, Dominion of Canada, have invented certain new and useful Improvements in Grain-Saving Attachments for Binders, of which the following is a specification.

10 This invention has relation to certain new and useful improvements in a grain saving attachment for a binder and has for its primary object the provision of a simple attachment which may be readily applied 15 to the compressor shaft, near the trip hook to straighten the grain and prevent loss thereof while in the binder.

I appreciate that there are a number of pertinent patents in the art of a nature 20 analogous to my present invention, intended for retaining cut grain in alignment upon the grain deck of the binder until the sheaf is formed and properly tied. These devices, however, are inadequate, in that they are 25 fastened to the trip hook and when a quantity of grain bears thereagainst, the combined weight of the attachment and the grain trips the trip hook before the sheaf is completely formed.

30 To obviate the factors subversive to the efficiency of this device, I mount my invention upon the compressor shaft of the binder and in axial alignment therewith so that very little additional leverage is applied 35 thereto, and in such a manner that it holds the grain in alignment with the trip hook until the sheaf is completely formed and released.

A further object of the invention resides 40 in the provision of an attachment of the character stated which may be applied to binders now in general use without material alterations therein and which will materially increase the efficiency of operation of 45 the binder by assuring a greater saving of the grain.

With the foregoing and other objects in view, as will appear as the description proceeds, the invention consists in the novel 50 construction, combination and arrangement of co-operating elements as hereinafter more specifically set forth, claimed and shown in the accompanying drawings forming a part of the present application, in which:

55 Fig. 1 is a fragmentary perspective view of a portion of a binder of conventional

form, with the attachment applied thereto.

Fig. 2 is a fragmentary detail perspective of the compressor shaft carrying the trip hook and showing the new attachment 60 applied to the compressor shaft.

Fig. 3 is a fragmentary detail section, substantially on the plane of line 3—3 of Fig. 2, looking in the direction indicated by the arrows. 65

Referring more in detail to the drawings in which similar reference characters designate corresponding parts throughout the several views, it will be seen that the compressor shaft 5, working beneath the grain 70 deck 6, carries the trip hook 7 near its end and the hook is retained in adjusted position by a set screw 8 or other suitable means carried by the collar 9 of the arm 10 supporting the trip hook 7. The trip hook 7 75 works through an elongated slot 11 extended inwardly from the edge of the grain deck 6, as shown in Fig. 1.

The present attachment, which is termed a grain saving attachment, comprises a 80 curved hook or finger 12 which is pointed toward its free upper end and works through a slot 13 provided in the grain table 6, parallel with the slot 11 and a suitable distance from the same, the slot 13 being somewhat shorter than the slot 11. The hook or finger 12 of the attachment has its lower end secured on the side of the supporting arm 14, at the free extremity thereof and a supporting arm 14 is extended at 90 a right angle from the shaft extension rod 15. By referring to Figs. 2 and 3 it will be seen that the shaft extension rod 15 has an enlarged end in the form of a socket 16, for removable engagement over one extremity 95 of the compressor shaft 5, near the collar 9 of the supporting arm 10 for the trip hook 7. A pin 17 or other suitable means is employed for fastening the socket 16 on the extremity of the shaft 5. When the pin 17 100 is employed, it is extended through the socket 16 and the end of the shaft 5, as clearly shown in Fig. 3. When the attachment is in proper position on the compressor shaft 5, the arm 14 is parallel with the arm 10, so that the hook or finger 12 may work properly through the slot 13, while the trip hook 7 works through the slot 11 of the grain table 6.

It is believed the complete construction 110 and operation of the attachment may now be apparent from the foregoing paragraphs

taken in connection with the accompanying drawings, without further detail description. It may be briefly stated, however, that the attachment may be readily applied to the compressor shaft and the slot 13 formed in the grain deck 6 so as to permit the hook or finger 12 to work through the slot 13 and co-operate with the trip hook 7 as the latter works through the slot 11, so as to keep the grain straight on the grain deck 6 and prevent loss of the grain in the binder. This is due to the fact that the hook or finger 12 works on the same shaft as the trip hook 7 and engages the grain near the head thereof, while the trip hook 7 engages the grain stalks near the centre thereof, in the usual manner. This should be clearly apparent to parties familiar with binders, without further explanation.

20 While the preferred embodiment of the invention has been disclosed it is to be un-

derstood that minor changes in the details of construction, combination and arrangement of co-operating elements may be resorted to within the scope of what is claimed, 25 without departing from the spirit of the invention.

What I claim as new is:

The combination with a grain deck, compressor shaft and trip hook of a binder, of 30 a grain holding device including an extension for the binder compressor shaft; an arm extended at right-angles from the free end of said extension; and a finger carried upon said arm in spaced relation to the 35 binder trip hook and designed for co-operation therewith to keep the grain in alignment upon the grain deck of the binder until the sheaf is formed and discharged.

In testimony whereof, I affix my signature.

ABRAHAM G. ENS. [L. S.]
